UNITED STATES PATENT OFFICE.

ALEXANDER McCREERY, OF HIAWATHA, KANSAS.

TIMING-GEARING.

1,195,247.

Specification of Letters Patent. Patented Aug. 22, 1916.

Original application filed May 25, 1915, Serial No. 30,404. Divided and this application filed September 22, 1915. Serial No. 51,957.

To all whom it may concern:

Be it known that I, ALEXANDER McCREERY, a citizen of the United States, residing at Hiawatha, in the county of Brown and 5 State of Kansas, have invented certain new and useful Improvements in Timing-Gearings, of which the following is a specification.

The present invention relates to gearing 10 and more particularly to the setting and timing gearing forming a part of the motor driven plow for which on the 25th day of May 1915, I filed an application for patent in the United States, Serial No. 30,404 and 15 of which this application is a division.

The motor plow is adapted to be steered by power derived from the same motor utilized for propelling the implement, or machine, over the field. The steering in either 20 direction may be determined in advance of throwing the gearing into action. This is effected by a setting mechanism under control of the operator and a timing mechanism which is automatic in its action after being 25 started.

The present invention relates to the setting and timing mechanisms and has for its 30 object to provide means which are under control of the operator to admit of setting the steering mechanism so as to turn the implement either to the right or to the left and, furthermore, to provide independent means whereby the power steering mechanism may be set in advance to turn the implement to the required degree, the power 35 mechanism being automatic in its operation after being tripped to effect the steering and to return the steering mechanism to normal position.

With these and other objects in view, 40 which will readily appear as the nature of the invention is better understood, the same consists in the improved construction and novel arrangement and combination of 45 parts which will be hereinafter fully described and particularly claimed.

In the accompanying drawings has been 50 illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings,—Figure 1 is

a view in elevation of the setting and timing gearing embodying the invention, showing the same in coöperative relation with the power and steering gearing; Fig. 2 is a detail view showing more clearly the gearing between the power actuated and the timing gears; Fig. 3 is a plan view of the gearing shown in Fig. 1; Fig. 4 is a detail view in perspective of the clutch by means of which the power operated steering mechanism is thrown into action showing the tripping mechanism associated therewith; Fig. 5 is a detail view of the power actuated steering gearing showing the timing and tripping gearing in coöperative relation therewith; Fig. 6 is a sectional view of the timing gear and the setting mechanism associated therewith.

Corresponding and like parts are referred to in the following description and indicated in all the views of the drawings by the same reference characters.

It is to be understood that the parts are suitably mounted and disposed to coöperate in the manner set forth in the parent application herein identified.

The shaft 11 is connected with the motor, not shown, to be driven thereby. A bevel gear 138 loose upon the drive shaft 11 is in mesh with a bevel gear wheel 137 secured 85 to a vertically disposed shaft 136.

Upon the drive shaft 11 is splined a clutch member 168 which is adapted to be thrown into and out of engagement with a clutch member 169 formed with the gear 90 wheel 138. When the clutch member 168 is moved to a position clear of the clutch member 169 the machine may be steered by hand and the power steering mechanism thrown out of action. When the clutch 95 member 168 is moved into clutched engagement with the gear 138 the power steering mechanism is thrown into action to turn the machine to the right or to the left according to which gear wheels are thrown into 100 operative position. A shipper lever 170 is secured at one end to a frame bar and its opposite end is forked and engages the clutch member 168. The shipper lever 170 is resilient and normally exerts a pressure 105 to hold the clutch member 168 into clutched engagement with the gear 138. This tendency of the shipper lever 170 is overcome by means of an arm 171 projecting from a vertically disposed shaft 154. The shaft 154 110

is mounted in a bracket 172 so as to receive both a rotary and a vertical movement. An expansible helical spring 173 mounted upon the shaft 154 is confined between an arm 153 and the lower member of the bracket 172 and normally tends to hold the shaft 154 elevated with the arm 153 in the plane of a stop 152 depending from a gear wheel 144 which is designated as the timing gear. The 10 shaft 154 is adapted to be depressed by means of a shaft 174 which extends transversely of the machine and is provided in its length with a crank portion 175 adapted to be actuated by means of a manually operable part, not shown. The inner end of the shaft 174 is bent or formed with a lateral extension 176 which projects into the path of an extension of the shaft 154 and which extension preferably constitutes a 15 projection of the arm 153. The operation of these parts will be more fully described hereinafter.

A vertical shaft 125 is provided at its lower end with a gear wheel 126 which is 20 in mesh with a pinion 127 secured to a shaft 44 which is connected with the steering wheels, not shown, and adapted to be reversely driven by means of the motive power. A pinion 128 is secured to the upper 25 end of the shaft 125. A pinion 129 is secured to the lower end of the shaft 125. A rack bar 130 is arranged to engage the teeth of the pinion 128. A rack bar 131 is disposed to engage the teeth of the pinion 129. 30 These rack bars 130 and 131 are adapted to be positively actuated and impart a corresponding rotary movement to the shaft 125. The rack bars 130 and 131 are disposed upon opposite sides of the shaft 125 and are arranged so that only one rack bar at a time 35 engages a pinion, hence the shaft 125 is adapted to be turned in one direction or the other upon a rack bar transmitting movement thereto through the coöperating pinion. The rack bar 131 is connected at one 40 end to the crank portion 133 of the shaft 132. The rack bar 130 is connected at one end to a wrist pin 135 attached to a gear wheel 134 secured to the shaft 132. These 45 rack bars are adapted to be moved simultaneously to throw one rack bar into engagement with one of the pinions 128 or 129 and at the same time to throw the other rack bar out of engagement with the remaining pinion. Movement of the rack bars is effected 50 by means of a bar 185 which has connection therewith and which extends within convenient reach of the operator to be actuated when it is required to throw the steering mechanism into action. Movement of the 55 bar 185 in one direction throws the rack bar 131 into engagement with the pinion 129 and at the same time moves the rack bar 130 out of engagement with the pinion 128. A reverse movement of the bar 185 throws the

rack bar 130 out of engagement with the pinion 128 and the rack bar 131 into engagement with the pinion 129. Inasmuch as the shaft 125 is geared to the steering shaft 44 the latter will be driven in one direction or the other according to which one of the rack bars is thrown into engagement with the coöperating pinion on the shaft 125. 70

The shaft 132 is vertically disposed and provided with the crank portion 133 in any manner and the gear wheel 134 is attached to the upper end of such shaft so as to rotate therewith. The shaft 136 is vertically disposed and provided with gear wheels 139 and 140 which are secured thereto. The gear wheel 139 is in mesh with the gear wheel 134 whereas the gear wheel 140 is in mesh with the gear wheel 141 mounted upon a shaft 142. A gear wheel 143 mounted upon the shaft 142 is connected with the 80 gear wheel 141 to rotate therewith and is in mesh with a timing gear 144. The gear wheels 134 and 144 are in different vertical planes and determine the degree of turning of the steering wheel of the machine. The gear wheel 134 has portions of its teeth cut away as indicated at 145 and 145^a. These cut away portions are diametrically disposed and admit of the gear 139 rotating without imparting any movement to the gear wheel 134 at certain times. The gear wheel 134 is provided with projections 146 and 147 upon its underside to engage with a projection 148 of the timing gear 144. The timing gear 144 has a part of its toothed portion cut away, as indicated at 149, thereby permitting of the gear wheel 143 to rotate without imparting any movement to the gear wheel 144 when the latter occupies a 90 position with the space 149 opposite the gear wheel 143. The gear wheel 134 is provided with projections 150 and 150^a which are adapted to be engaged by means of a spring detent 151, thereby holding the gear wheel 134 in a predetermined position during certain stages of movement of the steering mechanism. The timing gear 144 is formed upon its underside with a stop 152 which is 95 adapted to be engaged by an arm 153 secured to the vertically disposed shaft 154. The timing gear 144 is also provided with a stop 155 which is adapted to be engaged by a spring detent 156 to hold such timing gear in a given position. The timing gear 144 is provided upon its upper side with a plurality of teeth 157 which coöperate with a finger 158 which is adapted to be adjusted and set to regulate the degree of movement of the front and rear steering wheels. The finger 158 is loose upon the shaft 159 upon 110 which the timing gear 144 is mounted and has a rear extension 160 which is adapted to be engaged by a vertically movable sleeve 161 mounted upon the shaft 159. The rear extension 160 of the finger 158 inclines up 115 120 125 130

wardly away from the plane of the gear 144 so as to be engaged and depressed when the sleeve 161 is lowered, thereby rocking the finger 158 and disengaging its outer end 5 from the teeth 157. Ears 162 project upwardly from the finger 158 and are adapted to engage a finger 163 projecting outwardly from the sleeve 161 so that rotation of the sleeve 161 will effect a corresponding turning 10 of the finger 158 whereby the same may be set with reference to the teeth 157 of the timing gear 144. The finger 163 projects from opposite sides of the sleeve 161 thereby admitting of its rear end engaging the rear 15 extension 160 of the finger 158.

The sleeve 161 is adjustable vertically and rotatable at the will of the operator and is provided at its upper end with a gear wheel 164 whose teeth are adapted to be engaged by the teeth of a rack bar 165. This 20 rack bar has spaced upper and lower flanges which embrace the upper and lower sides of the gear wheel 164. Vertical movement of the rack bar 165 effects a corresponding adjustment of the sleeve 161 and a longitudinal movement of the rack bar imparts rotation to the sleeve 161 whereby the finger 158 may be turned in the desired direction with reference to the timing gear 144. The 25 rack bar 165 is attached to a shaft 166 which is mounted both to slide and turn. The shaft 166 extends preferably in a diagonal direction across the machine and terminates within convenient reach of the operator so 30 that the shaft may be manipulated to set the steering mechanism for automatic operation by the motive power. Rotation of the shaft 166 in one direction lowers the sleeve 161 and effects a tilting of the finger 158 35 whereby the same is disengaged from the teeth 157 and brought into locking engagement with the finger 163 by causing the ears 162 to project along opposite sides of the finger 163. It will thus be understood that 40 the initial movement of the shaft 166 results in disengagement of the finger 158 from the timing gear 144 and the engagement of such finger with the finger 163. The second movement of the shaft 166 is 45 longitudinal whereby the sleeve 161 is rotated to bring the finger 158 in the desired position with reference to the timing gear 144 according to the required degree of turning of the machine when steering the same. 50 After the finger has been brought to the required adjusted position the shaft 166 is rotated in the reverse direction, thereby lifting the sleeve 161 and admitting of the outer end of the finger 158 dropping into engagement with certain teeth 157. When the 55 sleeve 161 is elevated it is retained in place by means of a spring catch 167 which is attached to the upper end of the bracket 167^a in which the upper end of the shaft 159 is mounted. The setting of the finger 158 de-

termines the degree of turning of the steering wheels of the machine.

When it is required to throw the power steering mechanism into gear the manually operated part, not shown, is actuated to impart a rotary movement to the shaft 174. This movement is such as to depress the shaft 154 by causing the extension 176 to press upon the projection 153. 70

Under normal conditions the power actuated steering mechanism is disconnected from the motor by means of the clutch which, as stated, is effected by means of the shipper lever 170 and the arm 153 and operating stop 152. When it is required to 75 throw the power steering mechanism into gear the shaft 174 is turned as just stated, in a direction to bring the arm or projection 176 into action so as to depress the shaft 154, thereby moving the arm 153 away 80 from the stop 152. This releases the shaft 154 which is turned by the action of the resilient shipper lever 170 which results in throwing the clutch into engagement and the power steering mechanism into action. 85 The return movement of the shaft 154 to its given position brings the arm 153 into the plane of the stop 152 so that in the final movement of the timing gear 144 in the manner hereinafter stated the stop 152 will 90 engage the arm 153 and turn the shaft 154 so as to bring the arm 171 thereof into operative engagement with the shipper lever 170 to throw the clutch member 168 so as to 95 effect disengagement of the clutch and a 100 throwing of the power steering mechanism out of action.

The gear 143 for operating the steering mechanism normally occupies the relation illustrated most clearly in Fig. 5, that is with 105 one tooth in mesh with a tooth of the timing gear 144 adjacent the space 149. The stop 148 of the timing gear 144 is at one side of the stop 147 of the gear wheel 134. When the clutch member 168 is thrown into engagement with the gear wheel 138 the shaft 136 is set in motion in the direction indicated by the arrow, thereby moving the timing gear the distance of one tooth and bringing the gear wheel 143 opposite the 110 space 149. At the same time the stop 148 engages with the stop 147 and moves the gear wheel 134 a distance sufficient to bring the toothed portion at one side of the space 145^a into mesh with the gear wheel 139, 115 thereby rotating the gear wheel 134 and the shaft 132 and operating the rack bars 130 and 131 with the result that the shaft 125 is rotated in one direction or the other according to which one of the rack bars is in 120 engagement with the gear wheels 128 or 129. The gear wheel 134 makes a half revolution, thereby bringing the space 145 opposite the gear wheel 139, the gear wheel 134 being held in the adjusted position by means of 130

the spring detent 151 engaging the stop 150^a. When the gear wheel 134 has moved to bring the space 145 opposite the gear wheel 139 the gear wheel 134 comes to rest 5 and the stops 146 and 147 will have exchanged positions. Preliminary to the stopping of the gear wheel 134 the stop 146 engages the stop 148 of the timing gear 144 and moves the latter to throw the space 149 10 out of register with the gear 143, thereby bringing a tooth of the gear wheel 144 in the rear of the space 149 in mesh with the gear 143 whereby the timing gear is rotated until the finger 158 comes in contact with 15 the stop 146 and moves the gear wheel 134 a distance to throw the space 145 out of register with the gear 139, thereby bringing the toothed portion of the gear wheel 134 in mesh with the gear wheel 139 whereby the 20 gear wheel 134 is returned to normal position resulting in the resetting of the steering mechanism. During this operation the timing gear 144 continues to rotate until the stop 152 is brought in contact with the arm 25 153 and turns the shaft 154, thereby bringing the arm 171 in engagement with the spring shipper 170 by means of which the clutch 168 is disengaged from the gear 138, thereby throwing the power steering mechanism 30 out of action. The timing gear 144 comes to rest with the stop 155 engaged by the detent 156 and with a tooth of the timing gear at one side of the space 149 in mesh with the gear 143. The direction of 35 the steering is under control by movement of the bar 185 in the manner stated so as to throw one or the other of the rack bars 130 and 131 into engagement with the co-operating gear wheel according to the desired rotation of the shaft 125 to be effected.

Having thus described the invention, what is claimed as new is:—

1. A steering mechanism comprising shiftable gearing under control of the operator to admit of steering either to the right or to the left, an operating gear having the shiftable members connected thereto for operation, a power actuated member, and connecting gearing between the power actuated member and the operating gear including a timing mechanism for determining the degree of steering.

2. In steering mechanism, an operating gear, a timing gear, co-operating gears and stops between the timing gear and operating gear, and setting means for the timing gear under control of the operator including an axially movable and rotative member.

3. In steering mechanism, an operating gear, a timing gear, co-operating gears and stops between the timing gear and operating gear, setting means for the timing gear under control of the operator including an axially movable and rotative member, and

an operating member movable longitudinally and pivotally and having engagement with the axially movable and rotative member for imparting the two movements thereto.

4. In steering mechanism, an operating gear, a timing gear, connecting means between the operating and timing gears, a setting mechanism for the timing gear including a gear element mounted to receive longitudinal and rotative movement, and a rack bar having engagement with the gear element and mounted to receive a pivotal and a longitudinal movement whereby said gear element may be moved longitudinally and rotatively.

5. In steering mechanism, an operating gear, a timing gear, connecting means between the two gears, a finger adjustable with reference to the timing gear and adapted to impart a slight movement to the operating gear at a certain stage in the operation of the steering mechanism, a gear element mounted to receive a longitudinal and a rotative movement and adapted to disengage the finger from the timing gear and further adjustment thereof, a rack bar engaging the gear element and adapted to move the same longitudinally and rotatively, and means for holding the gear element when moved away from the said finger.

6. In steering mechanism, an operating gear, a timing gear, connecting means between the two gears, a finger mounted to receive a rocking and a turning movement and adapted to engage the timing gear in the normal adjusted position thereof and to engage and impart a movement to the operating gear, a gear element movable longitudinally and rotatively and adapted to engage the finger to move the same to an adjusted position, and a rack bar under control of the operator and having engagement with the gear element to effect longitudinal and rotary movement thereof.

7. In steering mechanism, an operating gear, a timing gear, connecting means between the two gears, a power shaft, gearing between the power shaft and timing and operating gears, the same including a clutch, a shipper member for the clutch, connected arms, one adapted to engage the shipper member to normally hold the same in restraint and the other adapted to engage the stop of the timing gear to be moved thereby for throwing the steering mechanism out of action, and means under control of the operator for tripping the arms to effect release of the timing gear and shipper member whereby the steering mechanism is thrown into action.

8. In steering mechanism, an operating gear, a timing gear, connecting means between the two gears, a setting mechanism under control of the operator for determin-

ing the degree of action of the timing gear, a power shaft, gearing between the power shaft and timing and operating gears including a clutch, a shipper member normally holding the clutch out of action, arms mounted to turn and move in a direction parallel with the axis about which they turn, one of the arms normally engaging the shipper member to hold the same in restraint and 5 the other arm engaging the timing wheel, and means under control of the operator for tripping the said arms to effect release of the timing wheel and shipper member whereby the steering mechanism is thrown into 10 gear.

9. In steering mechanism, the combination of a timing gear having a portion of its teeth omitted to provide a space, an operating gear having oppositely disposed 15 spaces formed by omission of the teeth, stops between the timing and operating gears, connected gears for imparting movement to the timing and operating gears and adapted to engage the spaces thereof, means 20 for holding the operating gear when its space comes opposite the driving gear, a setting mechanism mounted upon the timing

gear for throwing the operating gear into action, a power shaft, gearing between the power shaft and the beforementioned gears 30 including a clutch, a shipper member for the clutch, connected arms normally holding the shipper member in restraint and engaging the timing wheel, and operating means for effecting release of the shipper member and 35 timing wheel to admit of throwing the steering mechanism into gear.

10. Steering mechanism including rack bars, coöperating gears, means for throwing either one of the rack bars into engagement 40 with its coöperating gear, a shaft having the rack bars coupled thereto by means of a crank connection, a power shaft, a clutch for throwing the power shaft into and out of action, a shipper member for the clutch, operating means for the shipper member including a shaft having projections one of which is adapted to coact with the shipper member, an operating member, and a stop carried by the operating member to engage 45 with another projection of the shaft and arrest the operation of the parts.

In testimony whereof I affix my signature.
ALEXANDER McCREREY. [L.S.]
